(57) **CLAIM**

The ornamental design for a remote control for pet training, as shown and described.

DESCRIPTION

FIG. 1 is a front elevational view of a remote control for pet training showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof; and,

FIG. 8 is a back perspective view thereof.

The elements depicted in broken line in FIG. 2 represent unclaimed features of the remote control for pet training and form no part of the claimed design.

1 Claim, 7 Drawing Sheets
